(57) **CLAIM**

The ornamental design for a high intensity discharge lighting fixture, as shown and described.

DESCRIPTION

FIG. 1 is a perspective view of a high intensity discharge lighting fixture showing our new design as viewed generally from the top front and right side.

FIG. 2 is a perspective view taken generally from the top rear and left side.

FIG. 3 is a front elevational view thereof.

FIG. 4 is a right side elevational view thereof.

FIG. 5 is a rear elevational view thereof.

FIG. 6 is a left side elevational view thereof.

FIG. 7 is an enlarged top plan view thereof; and, FIG. 8 is an enlarged bottom plan view thereof.
